UNITED STATES PATENT OFFICE.

HARRY RANDOLPH VAN DEVENTER, OF NEWARK, NEW JERSEY, ASSIGNOR TO
SPLITDORF ELECTRICAL COMPANY, OF NEWARK, NEW JERSEY, A CORPO-
RATION OF NEW JERSEY.

IGNITION DEVICE FOR INTERNAL-COMBUSTION ENGINES.

1,410,428.

Specification of Letters Patent. Patented Mar. 21, 1922.

Application filed April 7, 1919. Serial No. 288,101.

To all whom it may concern:

Be it known that I, HARRY RANDOLPH VAN DEVENTER, a citizen of the United States, residing at Newark, in the county of 5 Essex, State of New Jersey, have invented certain new and useful Improvements in Ignition Devices for Internal-Combustion Engines, of which the following is a description, reference being had to the accompanying 10 drawing and to the figures of reference marked thereon.

The invention relates to new and useful improvements in an ignition device for internal combustion engines, and more particularly to a high tension or jump spark ignition device, wherein the current is generated by a magneto generator.

In my prior Patent No. 1,257,155, granted February 19, 1918, I have shown and described an ignition device of the above character, wherein the current generating member is oscillated by springs put under tension and the spark is produced by electrodes having fixed relation to each other. These 25 parts are all mounted upon a unitary bracket structure.

The present invention relates to improvements in the ignition device of my former patent, and has for an object to provide 30 an arrangement of the spark plugs, whereby the points are disposed at an incline to the vertical, so that any oil that may collect thereon will readily run off from the same, thus preventing the electrodes from becoming 35 fouled in use.

A further object of the invention is to provide an ignition device of the above character, wherein the bracket which supports the magneto generator forms one of the electrodes of the spark plug.

A further object of the invention is to provide a spark plug for an ignition device of the above character, wherein one of the electrodes is adjustable so that the distance 45 between the spark electrodes may be readily varied.

A still further object of the invention is to provide means whereby the timing of the release of the trip lever by the push rod 50 may be readily varied.

These and other objects will in part be obvious and will in part be hereinafter more fully disclosed.

In the drawings—

Figure 1 is a view partly in side elevation and partly in vertical section, showing an ignition system embodying my improvements;

Figure 2 is a view partly in front elevation and partly in section of the same;

Figure 3 is a detail showing the trip lever and the construction of the end of the push rod which operates upon the same;

Figure 4 is a vertical sectional view, showing a slightly modified form of the electrode 65 construction for the ignition device and also a modified form of holding means for supporting the bracket on the engine cylinder;

Figure 5 is a front view of a portion of the bracket, showing the holding means;

Figure 6 is a vertical section showing a further modification of the arrangement of the sparking electrodes.

The invention consists broadly of a magneto generator, wherein the current generating member is oscillated by springs put under tension by a push rod which in turn is operated by the engine, said push rod being tripped from connection with the trip lever, so as to permit the springs to actuate the current generating member at the proper time interval. Associated with the magneto generator are fixed electrodes, and the current jumps from one electrode to the other forming the well known jump spark.

The electrodes and the generator are both mounted upon a unitary bracket structure which is preferably made of sheet metal stamped and bent to the proper shape. The bracket is so constructed at the part where 90 the electrodes are supported that said electrodes will be held in an inclined position relative to the vertical, so that any oil collecting thereon will readily run off from the electrodes and thus prevent said spark plug 95 from becoming fouled in use.

In one embodiment of the invention, the bracket itself forms one of the electrodes and serves the double function of forming an electrode and supporting the magneto 100 generator. In another form of the invention, one of the electrodes is mounted in the bracket, so that it may be readily adjusted. The trip lever for actuating the current generating member of the magneto 105 generator is disengaged from the push rod

by means of a cam which is adjustable so as to vary the time of tripping said lever.

The invention will be more clearly understood by a brief reference to the drawings, in which I have shown my ignition device as consisting of a magneto generator G, which may be of the construction shown in my prior patent, above referred to. The current generating member is provided with 10 a shaft 1, which is actuated by springs 2—2 which may be connected to the end plate of the generator. The springs are connected to a trip lever 3, which is fixed to the shaft of the current generating member. The 15 magneto G is mounted on a bracket 4, which is preferably made of stamped sheet metal and consists of a supporting base plate 5 and a laterally projecting shelf 6, to which the magneto generator is bolted. The sup- 20 porting base 5 is provided with suitable openings 7, as shown in Figure 2 of the drawings, through which said bracket may be bolted to the engine cylinder. The bracket is formed with an outwardly pro- 25 jecting part 8, which forms a pocket 9 and this pocket 9 is disposed directly opposite an opening 10 in the cylinder wall. A spark plug 11, which may be of the ordinary construction, is threaded into a suitable opening 12 formed in said bracket, and it will be noted that the electrodes of the spark plug are arranged in an inclined direction relative to the vertical, so that any oil collecting on these electrodes will readily run off from 35 the same and prevent the spark plug from becoming fouled in use.

The trip lever is moved to cocked position and released by a push rod 13. This push rod 13 is pivoted at 14 to the valve rod 15 of the engine and the valve rod 15 slides in a housing 16 formed in the supporting plate 5 of the bracket. A spring 17 normally forces the push rod 13 in an upward direction and holds the same in position, so that 40 the end 18 of the push rod will engage a shoulder 19 on the trip lever 3. Said push rod is formed with a cam surface 20, which is adapted to make contact with an adjustable cam 21, carried by a lever 22, which is piv- 45 oted at 23 to the bracket. The edge of the bracket is bent forwardly and formed with a series of teeth 24, which are adapted to be engaged by the lever 22, so that the cam 21 may be held in various adjusted positions. 50 As the push rod moves forward, the end 18 thereof will engage the shoulder 19 and move the trip lever to cocked position, the cam surface 20 coming into contact with the cam 21 will force the push rod in a down- 55 ward direction and finally release the end thereof from the trip lever and this permits the springs 2 to quickly oscillate the armature or current generating member of the magneto generator. By adjusting the lever 60 22, the position of the cam 21 may be varied

and this as will readily be seen, will vary the time of release of the trip lever.

The projecting portion 9 carrying the spark plug is also formed with an opening 25, in which a charging cup 26 may be placed, so that gasoline may be placed therein and a charge of gasoline thus introduced in the engine cylinder in and about the electrodes of the spark plug, thus priming the engine for starting.

In Figures 4 and 5 of the drawings, I have shown a slightly modified form of means for supporting the bracket. In this form of the invention, the bracket is provided with an outwardly projecting part 27, 75 which has a bearing plate 28 at the vertex thereof. A bracket 29 is secured to the engine and this bracket is bent so as to overhang the portion 27. A bolt 30 is threaded into the bracket 29 and bears against the plate 28. When this bolt is screwed in it forces the magneto supporting bracket against the engine cylinder and thus holds the bracket firmly in place. In these figures of the drawings, I have also shown a modified arrangement of the spark plug. One of the electrodes, indicated at 31, is mounted in suitable insulating material 32, which is of the usual form in spark plug construction. Co-operating with this electrode 31 is a second electrode 33, which is threaded into the bracket and is formed with a knurled head 34 with which a spring 35 makes contact. By turning this knurled head the electrode 33 may be moved into or 90 out of the bracket and thus the distance between the end of this electrode 30 and the side face of the electrode 31 varied. It will be noted that the electrode 33 is connected directly to the bracket and therefore one 95 of the electrodes of the spark plug is connected to the generator through the bracket which supports the generator, while the other, of course, is insulated and connected by suitable wire to the generator, as indicated at 36 in Figure 1 of the drawings.

It will also be noted that the electrodes 31 and 33 are inclined to the vertical, so that any oil collecting thereon will quickly run off from the electrodes, as has been described 100 in connection with the arrangement shown in Figure 1.

In Figure 6 of the drawings, I have shown a further modified form of the invention. The electrode 31 is similar in construction 120 to that shown in Figure 4, but the co-operating electrode is in the form of arms 37 and 38, which are integral with the bracket supporting the generator. These arms are spaced from the electrode 31.

From the above description, it will be noted that I have provided an ignition device, wherein the spark is a jump spark and is produced by a magneto generator mounted on the bracket which supports the spark 130

plug. The means for actuating the magneto generator includes devices whereby the timing of the spark may be quickly varied. The spark plug is so arranged that the electrodes are inclined and any oil collecting thereon will quickly run off from the electrodes, thus preventing the spark plugs or electrodes from becoming fouled in use. Other advantages will be apparent from the 10 detailed description which has been given above.

It is obvious that minor changes in the details of construction and arrangement of parts may be made without departing from 15 the spirit of the invention, as set forth in the appended claims.

Having thus described my invention, what I claim as new and desire to secure by Letters Patent, is:

20 1. An ignition device including in combination, a magneto generator, a bracket supporting said generator, said bracket having means for supporting a spark plug with the electrodes thereof inclined to the 25 vertical.

2. An ignition device including in combination, a magneto generator, a bracket for supporting said generator, said bracket being bent so as to form a pocket adapted 30 to register with an opening in the wall of the ends of the cylinder, one wall of said pocket having an opening in which a spark plug is mounted, said wall being inclined so that the electrodes of the spark plug will 35 be inclined to the vertical.

3. An ignition device including in combination, a magneto generator, a bracket for supporting said generator, said bracket being bent so as to form a pocket adapted 40 to register with an opening in the wall of the ends of the cylinder, one wall of said pocket having an opening in which a spark plug is mounted, said wall being inclined so that the electrodes of the spark plug will

be inclined to the vertical, said wall of the 45 pocket supporting the electrodes having a charging top extending therethrough for priming the engine cylinder.

4. An ignition device including a sheet metal bracket having a vertical supporting 50 plate and a horizontal shelf, a magneto generator mounted on said horizontal shelf, said vertical supporting plate having a pocket formed therein adapted to register with an opening in the cylinder wall, said 55 pocket having means for supporting fixed electrodes, one of which is insulated and connected to the magneto generator and the other of which is connected through the bracket to the magneto generator. 60

5. An ignition device including a sheet metal bracket having a vertical supporting plate and a horizontal shelf, a magneto generator mounted on said horizontal shelf, said vertical supporting plate having a 65 pocket formed therein adapted to register with an opening in the cylinder wall, said pocket having means for supporting fixed electrodes, one of which is insulated and connected to the magneto generator and 70 the other of which is connected through the bracket to the magneto generator, said supporting means for the electrodes being disposed so that said electrodes are inclined to the vertical. 75

6. An ignition device including in combination, spark electrodes, a magneto generator, a bracket supporting said spark electrodes and said magneto generator, a bracket connected to the engine cylinder and overhanging the magneto supporting bracket, and a bolt threaded into said last named bracket and adapted to bear against the magneto supporting bracket for holding the same against the ends of the cylinder. 80 85

In testimony whereof I affix my signature.

HARRY RANDOLPH VAN DEVENTER.
